(57) **CLAIM**

The ornamental design for a wall tie, as shown and described.

DESCRIPTION

FIG. 1 is a perspective view of a wall tie of my new design; FIG. 2 is a front view of my new design, the rear view being a mirror image thereof;

FIG. 3 is a top plan view thereof;

FIG. 4 is a bottom plan view thereof;

FIG. 5 is a top plan view of a wall tie of my new design, where the elongated elements and the apertures therein are of indefinite length; and,

FIG. 6 is a right side view thereof, the left side view being a mirror image thereof.
